UNITED STATES PATENT OFFICE.

JOHN S. WHITE, OF PORTLAND, MAINE.

BRUSH.

SPECIFICATION forming part of Letters Patent No. 252,137, dated July 31, 1883.

Application filed March 5, 1883. (No model.)

To all whom it may concern:

Be it known that I, JOHN STAPLES WHITE, of the city of Portland, of the county of Cumberland, of the State of Maine, have invented 5 a new and useful Improvement in Brushes; and I do hereby declare the same to be described in the following specification and represented in the accompanying drawings, of which—

Figure 1 is a side view, Fig. 2 a vertical 10 and longitudinal section, and Fig. 3 a horizontal section, of a brush provided with my invention, the nature of which is defined in the claims hereinafter presented.

This brush, which is intended for use in washing windows or removing dust from walls, &c., is, as represented, ellipsoidal, though it may be ovoidal or spherical, or substantially so, in form. It consists of two concavo-convex 15 blocks, A A, having bristles B drawn into them by wires, and projecting from their outer or convex surfaces, such two blocks being arranged in manner as shown, and connected by two metallic thimbles, C C, adapted to them, respectively, and joined by a screw, D, going 20 through the head of one thimble and screwed into that of the other, as represented. Each of these thimbles may be screw-threaded in its interior space or bore, in order for it to screw 25 upon a handle or pole at one end thereof.

Instead of having two thimbles, one may be 30 used to extend into both blocks, and serve to connect or aid in connecting them together; or other proper means of connecting the blocks may be employed.

By having each block recessed or concave, 35 as well as convex, as shown, the confining-wires of the bristles of one do not interfere with those of the other, to prevent the flat surface of one block coming into close contact 40 with that of the other.

In order to prevent one block from turning out of place on the other, I provide them with

one or more dowels, a, inserted in them; or 45 one block may have one or more tenons to extend from it into the other.

With a brush consisting of two separate 50 brushes semi-spherical or ellipsoidal in form and arranged and fastened together substantially as described, there is little, if any, danger while using it of breaking a window or 55 injuring a surface against which it may be moved. It is especially useful as a railway-car-window cleaner.

I make no claim to a brush composed of two 60 semicircular blocks connected together and 55 having bristles projecting from their peripheries, all being as shown in the United States Patent No. 55,815. Nor do I claim a slate-cleaner and pencil-holder composed of a bottle and its stopper and sponges encompassing 65 them, as shown in the United States Patent No. 221,883. In my brush each of the blocks is not only convex laterally, but longitudinally, so as when supplied with bristles and placed and secured together a brush spherical, ovoidal, or ellipsoidal in form, or essentially so, is 70 produced, which differs materially from any brush or device shown in either of said patents.

I claim—

1. A brush composed of two separate semi-spherical or semi-ellipsoidal brushes arranged and provided with one or more connecting-thimbles, and a screw, adapted to them as 75 represented, for connecting them together, all being substantially as described.

2. A brush composed of two separate semi-spherical or semi-oval or ellipsoidal brushes, arranged and doweled or tenoned and connected together substantially as set forth.

JOHN STAPLES WHITE.
